UNITED STATES PATENT OFFICE.

ALBERT KLUGE, OF MILACA, MINNESOTA.

CURBING MOLD.

Application filed March 22, 1921. Serial No. 454,392.

To all whom it may concern:

Be it known that I, ALBERT KLUGE, a citizen of the United States, residing at Milaca, in the county of Millelacs and State of Minnesota, have invented new and useful Improvements in Curbing Molds, of which the following is a specification.

This invention relates to well curbing, the primary object of the invention being to provide a mold or form of such construction that curbing formed of plastic material, such as cement or the like, may be easily and quickly produced, wherein the curbing is properly formed and held until "set" and wherein the forms may be easily and quickly removed after the curbing plastic has hardened.

A further object of the invention is to provide mold or form devices of simple and inexpensive construction, which will be of light weight so as to be easily handled and yet which possess the necessary strength and rigidity to withstand the handling which they must receive, which are equipped with means for making proper depressions in the completed curbing to facilitate the application of novel handling means thereto, which may be locked firmly in proper or set up position, and which will prove thoroughly effective in operation.

With these and other objects in view, the invention consists of the features of construction, combination and arrangement of parts, hereinafter fully described and claimed, reference being had to the accompanying drawings, in which:

Figure 1 is a vertical longitudinal sectional view taken through a mold or form constructed in accordance with the invention and showing the same in the position the parts will assume when set up in position ready for operation,

Figure 2 is a side elevation of the exterior form,

Figure 3 is a horizontal sectional view taken upon line 3—3 of Figure 1,

Figure 4 is a view similar to Figure 2 and showing the exterior of the inner form.

Referring now more particularly to the drawings, 8 indicates the inner core or shell of the mold and 9 the outer shell thereof. These shells, as shown more clearly in Figure 3 of the drawings, are of cylindrical shape and are formed of thin sheet metal, the inner shell or core being of substantially smaller diameter than the outer shell. The

outer shell is formed of a pair of semi-cylindrical sections 10, connected together at one edge by means of hinges 11 so that the same may swing relative to each other, and the free edges of the sections 10 are equipped with barrels indicated generally at 12 adapted to register with each other when the said sections are swung to closed position, to receive a locking pin 13. The said free edges of the form sections are reinforced with strap iron as indicated at 14, while the inner or hinged edges of the said sections are similarly reinforced. The free edge of one of the sections 10 of shell 9 is turned outwardly so as to provide an extension 15 to act as a support when the body is closed.

The inner shell or core 8 is formed of semi-cylindrical sections as indicated at 16, the latter being connected at their adjacent edges at one side by hinges 17 disposed upon the interior surfaces of the said sections, and being provided at their free edges with barrels 18 adapted to register with each other to receive locking pin 19. The exterior surface of each of the core sections 16 is provided with outwardly projecting studs indicated at 20 arranged in uniformly spaced relation upon the said section. From an inspection of the drawings, and particularly Figures 3 and 4 thereof, it will be observed that the exterior surface of core 8 is free from obstructions save the outwardly projecting studs or formers 20, and it will be noted that these formers are arranged near one end of the said core.

When it is desired to cast or mold a well curbing, the outer and inner shells, 9—8 are arranged with respect to each other as shown in Figures 1 and 3 of the drawings. That is, the sections 10 are swung to closed position and locked by pin 13, while the sections 16 of the core 8 are similarly brought together. The core 8 is then disposed within the shell 9 concentric thereto, and the space indicated at 21 between the inner and outer shells is filled with the plastic of which the curbing is to be formed. After the plastic has become "set", the forms are unlocked by withdrawing pins 13 and 19, whereupon the said outer and inner shells may be removed from the tile or curbing. The curbing thus formed will be of hollow cylindrical construction, and upon the inner face thereof there will be depressions caused by the formers or lugs 20 of core 8.

While the above is a description of the invention in its preferred embodiment, it will be understood that various changes may be made in the minor details of construction and arrangement of parts without departing from the spirit of the invention as defined by the claims.

Having thus fully described my invention, I claim:

- 10 1. A mold for making well curbing comprising a cylindrical outer shell and a cylindrical inner shell adapted to be disposed in said outer shell, each of said shells comprising a pair of semi-cylindrical sections having abutting edge portions, the edge portions at one side of the shell being hingedly connected and the edge portions at the opposite side of the shell being provided with fastening means to detachably hold the same 15 connected and the shell closed, the said inner shell being provided in close proximity to one end thereof with an annular series of external projections to form a corresponding series of annular recesses in the outer 20 surface of a section of curbing molded between the shells, said projections being fixed to and projecting from the semi-cylindrical sections of said shell.

25 2. A mold for making well curbing comprising a cylindrical outer shell and a cylindrical inner shell adapted to be disposed in said outer shell, each of said shells comprising a pair of semi-cylindrical sections having abutting edge portions, the edge portions at one side of the shell being hingedly 30 connected and the edge portions at the opposite side of the shell provided with fastening means to detachably hold the same 35 connected and the shell closed, the said inner shell being provided in close proximity to one end thereof with an annular series of external projections to form a corresponding series of annular recesses in the outer surface of a section of curbing molded between the shells, said projections being fixed to and projecting from the semi-cylindrical sections of said shell.

nected and the shell closed, the said inner shell being provided near one end with an annular series of external projections fixedly secured to said semi-cylindrical shell sections to form a corresponding series of recesses in the outer surface of a section of curbing molded between the shells, one of the semi-cylindrical sections of the outer shell being extended and bent outwardly at right angles beyond the outer side of said shell to form a supporting flange, and reinforcing strips upon the free edges of said semi-cylindrical sections of the outer shell to bear against said flange when said shell sections are closed.

3. A mold for making well curbing comprising a cylindrical outer shell and a cylindrical inner shell adapted to be disposed in said outer shell, each of said shells comprising a pair of semi-cylindrical sections having abutting edge portions, the edge portions at one side of the shell being hingedly connected and the edge portions at the opposite side of the shell being provided with fastening means to detachably hold the same connected and the shell closed, the said inner shell being provided near one end with an annular series of external projections to form a corresponding series of recesses in the outer surface of a section of curbing molded between the shells, and one of the semi-cylindrical sections of the outer shell being extended and bent outwardly at right angles beyond the outer side of said shell to form a support separate from and independent of said fastening means.

In testimony whereof I affix my signature. 75
ALBERT KLUGE.
